tion of Illinois

Application March 2, 1951, Serial No. 213,657

7 Claims. (Cl. 200—16)

1

This invention relates to electric switches of the type in which a contactor, mounted on a shiftable carrier, is adapted to bridge and electrically connect selective ones of a group of contacts arranged over the surface of a common terminal board; and particularly to improvements in the form, construction, and mounting of the contactor means for such devices.

The main objects of this invention are to provide an improved shiftable contactor for group or unison engagement with a plurality of fixed contacts; to provide an improved mounting means for such a contactor; to provide an improved contactor capable of applying substantially equal contact pressure on each of a group of contacts, engaged in unison, regardless of variations in the relative heights of the several contacts and the effects of unequal wear on the contact surfaces, the contactor or both; to provide an improved articulating contactor; to provide an improved resilient suspension for such a contactor on the shiftable contactor carrier; to provide an improved carrier and contactor construction and assembly; and to provide a simplified carrier and contactor assembly which requires fewer parts and is more efficient in operation than similar devices heretofore known.

A specific embodiment of this invention is shown in the accompanying drawings in which:

Figure 1 is a plan view of the terminal face of a switch construction in which the improved contactor means is employed.

Fig. 2 is an end view of the same as seen from the line 2—2 of Fig. 1.

Fig. 3 is a transverse sectional view of the same as taken on line 3—3 of Fig. 1.

Fig. 4 is a similar sectional view of the same as taken on line 4—4 of Fig. 1.

Fig. 5 is a fragmentary longitudinal sectional view of the same as taken on line 5—5 of Fig. 1.

Fig. 6 is a perspective view of the switch of Fig. 1 with the terminal board partially broken away to show the contactors, and with one of the articulated contactor elements and its supporting springs shown in separated or exploded relation.

Fig. 7 is a diagrammatic view illustrating the action of the articulated contactor in its engagement with contacts of varying heights.

Fig. 8 is a view like Fig. 1 of a modified switch having a modified form of contactor suspension.

Fig. 9 is a perspective view of the same, similar to Fig. 6, showing the modified contactor suspension arrangement.

Fig. 10 is a fragmentary longitudinal sectional

2

view of the same as taken on line 10—10 of Fig. 3.

Fig. 11 is a diagrammatic plan view of the terminal board of the switch of Fig. 3 illustrating a typical multiple circuit arrangement in which a plurality of contacts are electrically connected to a common power source, the contactors being shown in dotted outline at the neutral switch position, and

Fig. 12 is a similar view showing the contactors shifted to engage a different contact group as in a typical switching operation.

As shown in the drawings the invention is embodied in a switch construction, such as is at present employed in automotive directional signal switches, and wherein the switch housing 1 is of arcuate shape and contains a similarly shaped terminal board 2 having a plurality of fixed contacts arranged in two rows; the housing, terminal board, and the rows of contacts extending along circular curves having a common center.

The housing 1 is generally in the form of an open pan, made of suitable sheet metal, and the terminal board 2 is of a suitable dielectric sheet material formed to rest directly on the edges of the housing side walls with its margins flush with the outer surfaces of the housing side walls, the terminal board being clamped in place by suitable ears 3, projecting from the housing side walls, through notches 4 in the terminal board margins and turned inwardly over the outer face of the terminal board.

The fixed contacts, numbered 5 to 10 inclusive, are in the form of rivets having hollow shanks 35 which extend through the terminal board 2. The beads of the rivets are disposed on the inside of the terminal board and provide the contacts, and the hollow shanks project outwardly from the outer side of the terminal board to provide terminals to which the necessary conductors are attached. As shown the contact rivets are secured to the terminal board in the usual manner, by staking the side wall material of the rivet shank over a washer, as at 11, and a spacer 12, of dielectric material, having suitable openings 40 to receive the contact rivet heads, is disposed on the inside face of the terminal board to provide a contactor slide surface substantially flush with the contact surfaces of the rivet beads.

A contactor carrier 13, curved about the same center as the housing and terminal board, is slidably mounted within the housing for movement along an arcuate path below the terminal board and this carrier contains the several contactors 45 by which selective ones of the several contacts

are electrically connected during the switching operations. The carrier 13, as shown, has an integral post 14, which projects through a slot 15 in the bottom wall of the housing, to provide a means for shifting the carrier.

The contactors herein shown and described, and in relation with which this invention is primarily concerned, are of two types. The first type is a single plate contactor intended for interconnecting two or more contacts; and the second type is an articulated contactor, having two sections, also intended to interconnect two or more contacts. Both types are floating contactors mounted in suitably shaped wells formed in the face of the carrier, on the side next to the contacts, and supported on resilient spring pillars which normally urge the contactors outwardly from the carrier toward the contacts and the terminal board. Also the well for each contactor is of greater depth than the maximum space between the carrier and the contacts so that the contactors can never become bound but are always floating regardless of the position of the carrier relative to the terminal board, in the assembled structure.

In the construction shown in Figs. 1 to 6, inclusive, wherein six contacts are provided, the plate contactors are adapted to connect two contacts of the outer row with one contact of the inner row and the articulated contactors are adapted for connecting the three contacts of the inner row, in the neutral position of the switch, and two of such inner row contacts at each of the right and left hand switch positions. Thus the plate contactors are triangular in plan and two are provided; the left hand contactor 16, referring to Fig. 1, being arranged to bridge the contacts 5, 6 and 8 when the carrier is at the end of its movement toward the right, and the right hand contactor 17 being arranged to bridge the contacts 6, 7 and 10 when the carrier is moved to the left from its neutral position, the common contact 6 being on a battery connection or power source terminal. The center contact 9 of the inner row of contacts is also on a battery connection or power source terminal and, at the neutral switch position, the articulated contactor connects the contacts 8, 9 and 10. When the carrier is shifted to the right the articulated contactor connects contacts 9 and 10, and when the carrier is shifted to the left the articulated contactor connects contacts 8 and 9.

In the manufacture of switches having a plurality of contacts mounted on a common terminal board it is virtually impossible to have all of the contact surfaces lying exactly in a common plane, particularly because during the staking operations the several contacts will be subjected to different pressures and will be forced into the surface of the terminal board by different amounts. This results in uneven or unequal contacting pressures from the contactors, during switching operations and when several contacts are engaged at the same time, in the ordinary switch constructions. The contactors, and the arrangements for mounting and supporting them, according to the present invention are intended to cure this difficulty.

As shown in Figs. 1 to 6, the plate contactors 16 and 17 are triangularly shaped members formed with a depending peripheral flange 29 and these members are mounted respectively in wells 18 and 19 formed in the carrier body adjacent its ends. Each plate contactor is provided with three contacting dimples, or rounded bosses 21, located

one in each of the three corners of the plate and projecting upwardly therefrom; and the bosses are spaced from each other substantially the same distance as the spacing of the contacts 5-6 and 5-8, or 7-6 and 7-10, which they are intended to engage.

The wells 20, in the carrier 13, are made to be of greater depth than the space between the top surface of the carrier and the adjacent face of the spacing strip 12, when the carrier is riding on the bottom of the housing 1; and the bottom of each well is provided with countersunk sockets 22, one below each dimple or boss 21, in which square ended helical springs 23 are seated. The springs 23 are held against lateral shifting by the sockets 22 and the contactor plate rests directly upon their upper ends, with its flange 20 projecting slightly below the surface of the carrier when the springs 23 are fully extended.

Thus, the plate contactors are equally supported at each of their corners, directly below each contacting dimple, and, because of the depth of the wells in which they are mounted, the contactors are full floating regardless of the position of the carrier in the housing and even though the carrier might be lifted, during operation, to such an extent as to ride against the spacer strip 12.

As shown the carrier 13 is provided with a plurality of slide bosses 24 on its bottom surface to minimize friction on the bottom of the housing during operation of the carrier.

The articulated contactor is disposed on the carrier 13, between the plate contactors 16 and 17, substantially on the same arc as the line of contacts 8, 9 and 10, and comprises a pair of contacting elements 25 and 26 mounted end to end in overlapping relation. In the form shown the elements 25 and 26 are identical in shape and each comprises an inverted pan-like member having depending side and end flanges, the end flanges 27 and 28 being rolled or rounded at their junction with the body of the pan-like member to provide upwardly projecting transversely extending beads or ribs 29. The end flange 27 extends entirely across the end of the pan-like member and the flange 28 extends for substantially half the width of the member, and the two elements 25 and 26 are positioned end to end with the half width flanges 28 in side by side relation.

The beads or ribs 29 are spaced apart, lengthwise of the contactor 25-26, the same distance as the spacing of the contacts 8, 9 and 10. Thus, since the extent of movement of the carrier 13, on either side of the middle or neutral position, is the same as the angular spacing of the contacts, the end ribs or beads of either, or both, of the elements 25 and 26 will always be engaged with two next adjacent contacts at any switch position.

The articulated contactor 25-26 is mounted on the carrier 13, in a well 30, in the same manner as the plate contactors 16 and 17, the well 30 being of greater depth below the depending edges of the end flanges 27 and 28 than the space between the carrier 13 and the spacer strip 12, and the bottom of the well being formed to seat the contactor element supporting springs 31. The springs 31 are square ended, and identical with the springs 23 which support the plate contactors 16 and 17, and two such springs are disposed below each of the elements 25 and 26.

The operation of the articulated contactor in its engagement with contacts of different heights is illustrated in Fig. 7, wherein the height difference of the contacts is shown somewhat exag-

gerated. From this view it will be seen that through the hinged or articulate action of the contactor 25—26, the contacts will be firmly and equally engaged even though all of the contacts in the series are of different heights and regardless of the switch position.

A modified arrangement for full floating support of the contactors is shown in Figs. 8 to 10 inclusive, wherein the invention is shown embodied in a switch like that of Fig. 1, but with the location of the contactors reversed to put the articulated contactor on the outer row of contacts. As shown in these views the contactors are of substantially the same form as heretofore described except that each contactor element is supported on a single spring in its respective carrier well.

Referring particularly to Figs. 8 and 9 it will be seen that each of the plate contactors 16.1 and 17.1 is provided with a downwardly projecting dimple or boss 32, on its bottom side, located at substantially the center of the plate area. A single tapered, or conical spring 33 is disposed in the plate well directly below the boss 32, the wide base of the spring being seated in a suitable socket in the bottom of the well and the narrow top end of the spring being of an inside diameter to fit and receive the boss 32. This central spring support for the plate contactors not only provides a uniform distribution of pressure between the several contacting elements 21.1, but also permits the contactor to rock about axes running between the centers of any two of the contacting elements thereby resulting in positive, equal pressure engagement with the fixed contacts regardless of their relative heights.

The articulated contactor, in this embodiment of the invention, as shown in Figs. 8, 9 and 10, is likewise provided with a single tapered or conical spring support for each of its elements 25.1 and 26.1, the respective springs 34 being centrally seated in the contactor well 30.1 and engaging a depending boss 35 located at the center of the respective contactor element. This single spring support permits uniform pressure to be exerted by each of the contacting ribs 29.1 and also permits rocking of each of the articulating elements to accommodate different levels of the fixed contact surfaces.

A typical automotive directional signal circuit, in which the improved switch construction may be employed is shown in Figs. 11 and 12 to illustrate the manner in which the contactors function to connect a plurality of terminal contacts, the contactors being arranged as in the switch of Fig. 8. As shown the center terminal contacts 6 and 9, of the two fixed contact rows, are connected to the battery or power source; contact 6 being connected to the power source through the brake switch and contact 9 through an automatic flasher. Contacts 5 and 7 lead to the Right and Left rear stop lights respectively; and contacts 8 and 10 lead to the Right and Left front direction lights respectively. Thus, when the switch is in the neutral position shown in Fig. 11, the articulated contactor 25.1—26.1 engages the three contacts 5, 6 and 7, controlling the stoplights, so that both stop lights are under direct control of the brake switch. In this switch position the plate contactors 16.1 and 17.1 are disposed on opposite sides of the contact 9 and the contacts 8 and 10 are dead.

Figure 12 shows the contactor positions when the carrier has been shifted to the right, as when a right hand turn is to be indicated. In this

switch position the articulated or hinged contactor 25.1—26.1 engages contacts 6 and 7 only and the plate contactor 16.1 engages contacts 5, 8 and 9. Thus both the Right rear stop light and the Right front direction light are connected to the battery and automatic flasher, through the terminal contact 9, while the Left rear stop light remains under direct control of the brake switch through the terminal contacts 6 and 7. A shift of the carrier to the extreme left position similarly connects the contacts 7, 9 and 10 together, through the plate contactor 17.1, and connects contacts 5 and 6 through the contactor 26.1, so that the Right rear stop light remains under the control of the brake switch.

It shall be understood that, while this invention has been illustrated in connection with a directional signal switch of arcuate form, there is no intention to limit the invention to switches of any particular type; and that the invention is applicable to any switch construction wherein contactors are shifted over a plurality of fixed contacts for the purpose of connecting two or more of them together electrically.

The principal advantages of this invention reside in the improved construction and supporting arrangement of the shiftable contactors whereby more uniform engagement with the fixed contacts is obtained; and in the fact that the improved construction provides a good stable contact pressure, during all switching operations, with a minimum of spring pressure on the contactor elements whereby frictional resistance against movement of the carrier in the switch housing is minimized. Other primary advantages are to be found in the form and mounting arrangement of the contactors whereby they automatically accommodate themselves to various levels of contact surfaces to maintain a firm stable contact engagement at all switch positions; and in the simplified contactor and carrier construction which permits fewer parts in the switch assembly and hence a considerably lower manufacturing cost than the switch constructions heretofore used.

Although two embodiments of this invention have been herein shown and described it will be understood that details of the constructions shown may be altered or omitted without departing from the spirit of this invention as defined by the following claims.

I claim:

1. In a switch of the sliding contactor type comprising a terminal board having a plurality of uniformly spaced contacts on one face arranged along a common axis of alignment, and a shiftable contactor carrier mounted adjacent and parallel with said terminal board face, a pair of contactors mounted on said carrier in overlapping end to end relation and along the axis of alignment of said contacts, each contactor having a length sufficient to extend from center to center of two of said contacts, spring means between each contactor and said carrier for supporting the contactors individually and normally urging said contactors toward said contacts, and means to shift said carrier so as to move said contactors along the axis of alignment of said contacts.

2. In a switch of the sliding contactor type comprising a terminal board having a plurality of uniformly spaced contacts on one face arranged along a common axis of alignment, and a shiftable contactor carrier mounted adjacent and parallel with said terminal board face, a pair

of contactors mounted on said carrier in overlapping end to end relation and along the axis of alignment of said contacts, each contactor having a length sufficient to extend from center to center of two of said contacts, a well in said carrier opening toward said terminal board for receiving said contactors, individual spring means seated in said well below each of said contactors and normally urging them outwardly from said well independently of each other, and means to shift said carrier and move said contactors along the axis of alignment of said contacts.

3. In a switch of the sliding contactor type comprising a terminal board having a plurality of uniformly spaced contacts on one face arranged along a common axis of alignment, and a shiftable contactor carrier mounted adjacent and parallel with said terminal board face, a pair of contactors mounted on said carrier in overlapping end to end relation and along the axis of alignment of said contacts, each contactor having a length sufficient to extend from center to center of two of said contacts, a well in said carrier opening toward said terminal board for receiving said contactors in substantially parallel relation with said terminal board, a conical coiled spring seated in said well below each of said contactors, each spring having its smaller end bearing centrally on the bottom side of the respective contactor and normally urging the contactor outwardly, each contactor being individually supported by its spring and capable of independent tilting movement, and means to shift said carrier and move said contactors along the axis of alignment of said contacts.

4. In a switch of the class described comprising a terminal board having a plurality of uniformly spaced contacts on one face arranged along a common axis of alignment, and a shiftable contactor carrier mounted adjacent and parallel with said terminal board face, a pair of contactors mounted on said carrier in end to end relation along the axis of alignment of said contacts, said carrier having a well opening toward said terminal board and adapted to receive said contactors, a coiled spring seated in said well below each of said contactors and normally urging said contactors outwardly independently of each other, the adjacent ends of said contactors each having a projecting end flange of about one-half the contactor width and said end flanges being in side by side overlapping relation, a contacting element on each of said contactor end flanges and on each of the opposite ends of said contactors, the contacting elements on each contactor being spaced substantially the same distance as said contacts, and means to shift said carrier to move said contactors along the axis of alignment of said contacts.

5. In a switch of the class described comprising a terminal board having a plurality of uniformly spaced contacts on one face arranged along a common axis of alignment, and a shiftable contactor carrier mounted adjacent and parallel with said terminal board face, a pair of contactors mounted on said carrier in end to end relation along the axis of alignment of said contacts, said carrier having a well opening toward said terminal board and adapted to receive said contactors, a conical coiled spring seated in said well below each of said contactors with its smaller end engaging the contactor centrally, said springs

normally urging said contactors outwardly independently of each other, a boss on the bottom side of each contactor adapted to seat in the uppermost coil of the respective spring and permit tilting movement of the contactor relative to the axis of the spring, the adjacent ends of said contactors each having a projecting end flange of about one-half the contactor width and said end flanges being in side by side overlapping relation, a contacting element on each of said contactor end flanges and on each of the opposite ends of said contactors, the contacting elements on each contactor being spaced substantially the same distance as said contacts, and means to shift said carrier to move said contactors along the axis of alignment of said contacts.

6. In a device of the class described, an articulated contactor means for engaging three equally spaced and aligned contacts in unison, and for engaging either adjacent pair of said contacts upon shifting of the contactor along the axis of contact alignment, said contactor means comprising a pair of inverted pan-like plates disposed end to end and each having depending side and end flanges, the end flanges at the adjacent ends of said plates being of substantially half the width of the plates and being disposed in side by side overlapping relation, a contacting element on each end flange of each plate, the contacting elements of each plate being spaced apart along the axis of contact alignment substantially the same as said contacts, a shiftable carrier for said contactor, and spring means on said carrier for supporting each of said plates independently of the other.

7. In a device of the class described, an articulated contactor means for engaging three equally spaced and aligned contacts in unison, and for engaging either adjacent pair of said contacts upon shifting of the contactor along the axis of contact alignment, said contactor means comprising a pair of inverted pan-like plates disposed end to end and each having depending side and end flanges, the end flanges at the adjacent ends of said plates being of substantially half the width of the plates and being disposed in side by side overlapping relation, a contacting element on each end flange of each plate, the contacting elements of each plate being spaced apart along the axis of contact alignment substantially the same as said contacts, a shiftable carrier for said contactor, an outwardly opening well in said carrier for receiving said contactor, and a conical coiled spring seated in said well below each plate and having its smaller end centrally engaging the bottom side of the plate to support the same tiltably and independently of the other plate, said springs normally urging said plates outwardly from said well, and the flanges of said plates normally extending into said well to retain said plates against lateral displacement.

GILBERT S. ELLITHORPE.
